Nelson W. Howard

UNITED STATES PATENT OFFICE.

WILLIAM J. MACLEAN, OF BRIDGEWATER, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON THE SOLES OF BOOTS AND SHOES.

Application filed March 26, 1923. Serial No. 627,719.

This invention relates to machines for use in beating or pounding the bottoms of boots and shoes. In the manufacture of most shoes, more particularly women's shoes, it is important that, after the outsole has been attached, the margins of the sole at the shank portion of the shoe be bent toward the last so as to bring the surface of the welt, if it is a welt shoe, into contact with the upper and cause the so-called welt crease, that is, the angular space between the sole or welt and the upper, to be closed. This operation is frequently referred to as shank breaking and has usually been effected by hand, a hammer being used to pound or "pean" the edge or margin of the sole to bend it relatively to the plane of the body portion so as to close the welt crease and produce a close shank.

An object of this invention is to provide a machine adapted to beat the marginal portion of the sole into the desired position whereby the operation may be performed with less labor and more expeditiously than can be done by hand, and without liability of injury to the shoe upper or other parts of the shoe.

Features of the invention consist in a novel form of rotary beating element for delivering repeated blows upon a sole, in a duplex arrangement of such elements, and in novel means to guide the shoe with respect to such beating elements as the shoe is held to one of the beating elements by the operator's hands and to guard the upper and channel leaf from injury during the action of either element on either of the sole margins.

As shown, in one embodiment of the invention each element of the tool is provided with flat faces joined by rounded corners which, as the tool rotates, successively engage and beat the sole. The flat faces of each tool element may constitute the sides of the frustum of a pyramid. By moving the shoe toward the larger end of the element a greater beating effect will be secured. The illustrated tool element may also be regarded as cuboidal with two parallel faces, one smaller than the other and both perpendicular to the shaft, the other four faces being equal, equally inclined to the shaft, and joined by the rounded corners.

To guide the shoe with respect to the beat-

ing elements as the shoe is held to the tool in the operator's hands, a novel gage or guide is provided. The gage, as shown, may comprise a ring loosely mounted on the axis of the tool adjacent to the smaller end of each of the beating elements and slightly larger than the smaller end of the element so that its peripheral portion will extend enough beyond the corners of the element to form an obstruction to movement of the shoe lengthwise of the axis of the tool in the direction of the smaller end of the element and indicate the proper location of the shoe for the beating operation. The ring also serves as a guard for protecting the upper from injury and for this purpose may, as shown, have a relatively wide face lengthwise of the axis of the tool so that when, in order to cause either beating element to act upon the edge corner of the sole at the shank, or even upon its edge face, the shoe is tipped about its longitudinal axis, the upper will contact with the guard ring. Of course, as soon as either the edge of the sole or the upper touches the guard ring, its rotation is arrested and the shoe may rest against it without liability of the edge or the upper being defaced, while at the same time the shoe is freely movable lengthwise to subject the sole margin to the effective action of the beating tool.

In another embodiment of the invention the beating faces of the elements are illustrated as shortened so as to avoid engagement of the beating face with the channel leaf or lip and concentrate the beating action on the margin of the sole outside the lip. In this case a guide and guard ring may be provided between the tool elements or, as an alternative, the reduction to accommodate the channel leaf may be formed in the central portion of a tool the elements of which are smaller at their outer ends relatively to the central portion, and a separate ring may be provided adjacent to the smaller end of each element.

By these constructions both sides of the shank of the shoe may be treated to pounding action with a minimum of manipulation of the shoe, since one side of the shoe sole may be operated upon by the one element, its edge being held against one face of a gage or guard ring and its upper protected by the edge face of the said ring, and when

the operation upon that side of the shoe has been completed by moving the shoe laterally and without shifting the shoe end for end the other side of the sole may be presented 5 to the other element with its edge against another face of a gage or guard ring, the upper being guarded as before by the peripheral face of the ring. As shown, the tool and gage are mounted directly upon the 10 end of the shaft of a motor, such as an electric motor, properly designed to run at the speed required for the tools. This arrangement results in a greatly simplified construction of the machine and enables power to be 15 applied, without loss, to the tool and thence to the shoe.

In the drawings,

20 Fig. 1 is a perspective view of an electric motor having mounted upon its shaft beating mechanism embodying the present invention, a shoe being shown with the edge corner of the shank of the sole presented to the outer beating element of the duplex tool;

25 Fig. 2 is a side elevation of the tool, a shoe being shown in section with one side in operative relation to one element of the tool and its position indicated in dotted lines when the other side is presented to the other element; and

30 Figs. 3 and 4 are modified forms of duplex tools embodying the present invention.

In the drawings a motor is shown at 2 on the shaft 4 of which is extended to provide a support and actuator for a rotary tool 6, 18 35 which is secured to the shaft by set-screws 7. It is to be understood, of course, that any shaft suitably mounted and driven at the proper speed may be utilized to hold and drive the tool. Since, however, a proper speed for the tool is about 1200 R. P. M., it is convenient and advantageous to connect the tool directly to the armature shaft of a motor designed to run at that speed. The tool, as shown in Figs. 1 and 2, is made up 40 of two elements 6, 18 each of which is formed as a frustum of a four-sided pyramid with the corners between its inclined faces slightly rounded so as not to injure the leather of the sole. The bases of the elements 6, 18 are 45 arranged outwardly. Preferably, however, the taper of the acting faces of the element is only slight and the proportions of the element are such that it may be regarded as cuboidal, that is, the element presents a six-sided figure approximating a cube. The outer face or side 8 and the inner face 10 are unequal and parallel, both being perpendicular to the shaft 4. The other four faces 12, which constitute the acting faces 50 of the element, are equal and equally inclined to the shaft 4, the corners between these faces being slightly rounded to prevent too harsh action of the tool upon the work.

65 Adjacent to the inner and smaller ends of

the elements is arranged a ring 14 loosely mounted on the shaft 4, the ring being of such a size that it projects slightly, as at 15, beyond the corners of the tool. This projection is sufficient to arrest the shoe which is being upheld against either element 6, 18, and serves as a guide for the operator in properly locating the shoe with respect to the tool. The tapered formation of the element tends to hold the edge of the shoe against the gage. The operative may, if he wishes, however, move the shoe outwardly to cause a larger portion of the element to engage the sole, the beating effect there being greater because of the larger diameter of the element. 75 80

In treating some shoes having sharply curved or angular shanks it is necessary to turn the shoe about its longitudinal axis so as to present the edge corner of the sole, and even the edge face of the sole, to the beating element. In this event it is necessary to protect the upper from injury by contact with the tool. To thus protect the upper the gage 14 has its edge face 16 extended lengthwise of the shaft 4 to form a guard. With this guarding face 16 provided on the loose ring 14 the operator does not have to exercise care as to the amount he turns the shoe and may present the shoe to the beater in any position necessary to produce the desired beating effect. 95

Inwardly of the ring 14 on the shaft 4 is arranged the second beating element 18 which may be, and preferably is, identical with the element 6, this element being arranged with its smaller end next to the ring 14. From the drawing it will be clear that one side of the shoe may be presented to the element 6 as described, and then the opposite side of the shoe, simply by a lateral movement of the shoe, may be presented to the tool 18 and a similar operation performed on that side of the shoe, the opposite side face of the ring then serving as a gage and the same edge face 16 serving as a guard for the upper. This construction avoids the necessity of turning the shoe end for end as would be necessary if only one tool were provided. 100 105 110 115

In Fig. 3 is shown as form of duplex tool 115 having, broadly, the characteristics of that shown in Figs. 1 and 2. This form, however, is better adapted for beating the margins of soles which are channeled and have the channel leaf turned inwardly. It is 120 preferable to beat down the margins of such soles before the channel leaf is laid and to avoid contact of the tool with the channel leaf. Accordingly, in this form the beating face of each element of the tool is shortened 125 by cutting away the outer or larger portions of the elements as at 20. The beating faces of the elements 21, 21 are substantially circular and are provided with grooves 22 to enable the tool to effect a beating action 130

as well as a rubbing action. Between the elements a loose ring 24 is arranged, the said ring having the guiding and guarding functions ascribed to the ring 14 of Figs. 5 1 and 2.

In Fig. 4 is shown another form of duplex tool, the beating elements of which are arranged reversely to those of the other tools shown. Here the central portion of the tool 10 is reduced at 26 to provide clearance to accommodate the channel leaf when the margin of the shoe sole is presented to either of the beating elements 27, 29, and separate, loose guide and guard rings 28, 30 are provided, one at each end of the tool, each ring being located adjacent to the smaller end of a beating element as in the other construction shown.

In the operation of the machine the shoe 20 is firmly upheld in both hands of the operator and the marginal portion of its shank presented, for example, to the element 6 as shown in full lines in Fig. 2, the shoe being turned about its longitudinal axis and moved 25 lengthwise to cause the desired lateral and longitudinal extent of the sole margin to be beaten into the desired position to produce a close shank. When this operation has been effected on one margin of the shank the shoe 30 is shifted laterally to present the opposite margin to the other element, in this instance to the element 18 as shown in dash and dot lines in Fig. 2, and a similar operation on that margin is performed. During these 35 operations the opposite side faces 15, 17 of the loose ring respectively provide gages for the lateral position of the shoe with respect to the elements 6 and 18, and the edge face 16 of the ring serves in both operations to guard 40 the upper against injury when the shoe is turned about its longitudinal axis alternatively to present the opposite edge corners or edge faces of the sole to the action of the respective tools.

45 The form of tool shown in Fig. 3 is similarly used, the margin of the sole outside the channel leaf being first presented to one of the elements 21 as shown with the channel leaf lying in the cut-away portion 20 of the 50 element and then the other margin presented in a similar manner to the other element 21. In using the tool shown in Fig. 4 the shoe is held so that the upper is guarded by one of the loose rings, for example 28, with the 55 channel leaf in the cut-away portion 26, the margin of the sole being treated by the beating element 27. The edge of the sole is guided by engaging the inner face of the ring 28. The shoe is then moved laterally 60 to position the sole edge against the inner face of the loose ring 30, the edge face of which guards the upper. The margin of the sole is then treated by the element 29 while the channel leaf lies in the cut-away 65 portion 26 as before.

Having thus described my invention, what I claim as new and desire to secure by Letters Patent of the United States is:

1. In a shoe beating machine, a duplex tool having beating elements to treat the right and left sides of the shank, in combination with loose means to guard the upper when using either the right or the left element. 70

2. In a shoe beating machine, a duplex tool having beating elements tapered to adapt them for treating opposite sides of the shank portion of the sole without reversal of the shoe end for end, and a loose ring adjacent to the smaller end of each element to guard the upper when either element is in use. 75

3. In a machine of the class described, a rotary shaft, a duplex tool fixed on the shaft having tapered sole treating elements to treat right and left shanks, in combination with loose means adjacent to similar ends 80 of the elements, said means being arranged to engage the edge face of a sole while its margin is treated by the tool. 85

4. In a machine of the class described, a duplex tool having sole treating elements to treat right and left shanks, in combination with loose means comprising a single ring to cooperate by one edge with one of the beating elements and by its opposite edge with the other element. 90

5. In a shoe pounding machine, a rotary shaft, a pair of similar beating elements on the shaft for treating a shoe sole, said elements being symmetrically arranged with respect to a plane perpendicular to the shaft and adapted for alternative use in treating opposite marginal portions of the shoe sole, and a flange projecting beyond the beating faces of the tools and located in their plane 100 symmetry. 105

6. In a shoe beating machine, a pair of rotary beating elements, and shoe guiding and guarding means loosely arranged with respect to said elements, said elements and guiding and guarding means being arranged 110 in bilateral symmetry with respect to a plane perpendicular to the axis of rotation of the elements.

7. In a shoe beating machine, a rotary shaft, a plurality of beating elements fixed to the shaft for treating the sole, and a loose ring separating the elements. 115

8. In a shoe beating machine, a rotary shaft, a tool comprising a plurality of similar rotary beating elements on the shaft, and relatively movable means between the elements to serve as a guide for the work and a guard for the upper when either element is being used. 120

9. A shoe beating machine having, in combination, a rotary shaft, a plurality of similar beating elements on said shaft, the operating surfaces of said elements being oppositely inclined relatively to the shaft, and means for guiding the edge face of the sole 125 130

- while its margin is presented first to the action of one tool and then to the other tool.
10. In a shoe beating machine, a rotary shaft, a plurality of similar beating elements on the shaft, and a member between the tools loosely mounted on the shaft and arranged to be held stationary by contact with the work to serve as a guide for the work and as a guard for the upper when either element is being used.
11. A shoe beating machine having, in combination, a rotary shaft, a plurality of similar beating elements on the shaft, the operating surfaces of said elements being oppositely inclined relatively to the shaft, and means between the elements which becomes stationary when brought in contact with the shoe, said means acting as a guard for the upper when one margin of the shoe sole is presented to the action of one tool and likewise when its opposite margin with the lengthwise direction of the shoe unchanged is presented to the other tool.
12. In a shoe beating machine, a rotary shaft, a beating tool on said shaft, said tool having elements each formed as a truncated pyramid and arranged with its base perpendicular to the shaft and its truncated end toward the similar end of the other, and a loose ring between said elements to form an edge gage for a sole while being treated by either of said elements.
13. In a shoe beating machine, a rotary shaft, a plurality of beating elements on the shaft, said elements each having substantially the shape of a truncated pyramid, and a guide for the work adjacent to the truncated end of each element.
14. In a shoe beating machine, a rotary shaft, a plurality of beating elements on the shaft, said elements each having substantially the shape of a truncated pyramid, and a relatively wide loose ring adjacent to the truncated end of each element to guard the upper when the shoe is tipped in presenting
- the margin of the sole to the beating elements.
15. In a shoe beating machine, a rotary shaft, a plurality of similar elements fixed to the shaft for treating the sole, and a loose ring separating the elements.
16. In a shoe beating machine, a rotary shaft, a beating element on the shaft, said element having four equal operating faces inclined to the shaft, and a guide for the work adjacent to the ends of the faces nearest to the shaft and projecting beyond said faces.
17. A shoe beating machine having, in combination, a rotary shaft, a plurality of similar tool elements on said shaft, the operating surfaces of said elements being oppositely inclined relatively to the shaft, and means between the elements for guiding the edge face of the sole while its opposite margins are presented first one margin to the action of one element and then the other margin to the other element.
18. In a shoe beating machine, a rotary shaft, and a beating element on the shaft, said element having four non-parallel faces and two faces parallel, the shaft being perpendicular to the parallel faces.
19. In a shoe beating machine, a rotary shaft, and a beating element on the shaft, said element having two unequal parallel faces perpendicular to the shaft and four non-parallel faces equally inclined to the shaft.
20. In a shoe pounding machine, a rotary shaft, a pair of identically shaped beating elements reversely arranged on the shaft for treating the respective marginal portions of a shoe sole, and loose means on the shaft forming a guard for the shoe upper when a margin of the shoe sole is presented to either of said elements.

In testimony whereof I have signed my name to this specification.

WILLIAM J. MACLEAN.

CERTIFICATE OF CORRECTION.

Patent No. 1,659,147.

Granted February 14, 1928, to

WILLIAM J. MacLEAN.

It is hereby certified that error appears in the printed specification of the above numbered patent requiring correction as follows: Page 3, line 104, claim 5, after the word "plane" insert the word "of"; and that the said Letters Patent should be read with this correction therein that the same may conform to the record of the case in the Patent Office.

Signed and sealed this 2nd day of April, A. D. 1929.
